(57) **CLAIM**

The ornamental design for a display screen with a transitional graphical user interface, as shown and described.

DESCRIPTION

FIG. 1 is the first image in a sequence for a display screen with a transitional graphical user interface showing the new design; and

FIG. 2 is the second image thereof; and,

FIG. 3 is the third image thereof.

The broken line showing of the display screen is for environmental purposes only and forms no part of the claimed design. The appearance of the image transitions sequentially between the images shown in FIGS. 1-3. The process or period in which an image transitions to another forms no part of the claimed design.
